PICKLING CHAIN

John L. Gerber, Pittsburgh, Pa., assignor to
Bronze Die Casting Company, a corporation
of Pennsylvania

Application February 13, 1936, Serial No. 63,724

6 Claims. (Cl. 74—249)

This invention relates to an acid-resistant chain adapted to use in pickling machines.

In pickling machines of the type used in pickling such elongate stock as iron and steel pipes, tubes, rods, bars, and shapes, the elements subjected to the pickling solution are supported therein by means of at least two spaced chains. These chains, at both sides of the bath, pass over sprockets, or sheaves, which are operated frequently to change the shape of the loops formed by the two chains. As the chains recurrently change their loop form under the influence of the sprocket movement, the elements of the stock are tumbled in the pickling bath, rubbing against each other and against the chain, and washing the pickling solution against the surfaces of all the stock elements.

Problems arise in connection with the structure of these stock-supporting and stock-agitating chains. While commonly made of acid-resistant bronze, such bronze is not capable wholly of resisting the corrosive effect of the pickling solution. This gradually destructive corrosion proceeds slowly upon parts of massive form, which present relatively smooth uninterrupted surfaces to the pickling solution, but proceeds with relative rapidity in structures comprising closely adjacent surfaces between which the pickling solution may enter.

For the reason given above, it is undesirable to use in pickling machines chains comprising pins, rivets, bushings, and the like, such as are usually made structural elements in sprocket chains. Simple open-link chains, if formed without definite weld line and otherwise formed to present uninterrupted surfaces to the pickling solution, are capable of resisting long continued subjection to the corrosive effect of a pickling solution. Those chains, however, not being well adapted to use with sprockets, and as passed over sheaves, do not operate smoothly but on the contrary tend to kink, and by turning so to "snake" past the stock that the rubbing effect of the stock elements on each other is lessened, and wear in the chain itself is unduly increased by rubbing of the chain links against each other.

With these problems in mind, I have invented a chain for use in pickling machines which is massive, rather than complex, in structure; in which the chain links maintain their initially predetermined position with respect to each other; which is so formed that it provides receiving pockets formed to permit and positively to cause tumbling of the stock; and in which the links are so interconnected that the single, integrating

interruption in each link is so positioned in the assembly that corrosion at the locus of interruption in the several links results in the least damage to the chain structure as a whole.

Further, I have invented a sprocket chain which because of its strength, smooth running, and the fact that it may be used reversibly, is adapted to use in various associations other than with a pickling machine, and which may be made of other than acid-resistant metals.

In the accompanying drawing, Fig. I is a cross-sectional view through a pickling machine showing, somewhat diagrammatically, a chain made in accordance with my invention looped to support a plurality of elongate stock elements in the pickling solution, and mounted in manner to provide for change in the form of the stock-supporting loop of the chain.

Fig. II is a plan view, on the approximate scale of Fig. I, showing several links of my pickling chain joined, and showing an end link of this fragmentary chain structure open for connection with its next adjacent link.

Fig. III is a view, partially in side elevation and partially in section through an assembly of chain links, illustrating particularly the connection between adjacent links of the chain and the mode in which such connection is made.

Fig. IV is a view, partially in plan and partially in horizontal section, on the line IV—IV of Fig. III, illustrating a connection between chain links.

In Fig. I of the drawing, showing a pickling machine of the type above referred to, reference numeral 1 designates a trough or tank made of wood, or other suitable material, unaffected by the pickling solution, and reference numeral 2 designates the pickling bath. At both sides of the tank 1 are mounted sprockets 3, over which the chain 4 is passed. A number of stock elements 5, shown as bars of circular section, are supported in the pickling bath 2 by a loop of the chain dipping below the surface of the bath. It is to be understood that one or more additional chains are similarly mounted along the tank to support stock at different points along its length.

Considering specifically the structure of the chain links, each of these links, when viewed in side elevation, comprises a relatively broad portion formed of the link hub 6 and side flanges 7 projected radially therefrom. The hub flanges 7 merge into side arms 8, which are relatively narrow as viewed in side elevation, and which are interconnected at the end of the link opposite the hub by a cross-bar 9 carrying thereon a radially disposed protuberance, or lug, 10.

It is to be understood that each link, comprising as its primary elements the flanged hub 6, side arms 8, and cross-bar 9, may be made as a one-piece casting. One of the links is so shown in Fig. IV of the drawing, a dotted division line A—A intersecting the cross-bar at the lug 10 thereon being shown to indicate the line on which the cross-bar is interrupted as by sawing through it after the link has been cast. Connection between links is made in the manner shown in Fig. II, the link being opened by so spreading the side arms as to separate the terminals of the interrupted cross-bar a distance adequate to span the hub of an adjacent link. The terminals of the divided cross-bar are then brought into alignment with the hub bar of an adjacent link, and, the link being reclosed, the sections of the cross-bar are brought into close proximity to each other within their receiving hub bore.

Within the hub bore of each link is a channel 11, formed on a radius greater than that on which the exterior regions of the bore are formed, and extended through a portion of the bore circumference. The channel 11 is thus bounded by side walls 12 and by a shoulder 13 at which the channel terminates. Channel 11 is rendered accessible to the lug portions carried by each of the cross-bar sections, and the cross-bar is permitted to enter the hub bore, despite the protuberances on its divided sections, by way of a groove 14 through the side walls 12 of the hub and extending to the channel 11 interiorly of the hub.

In assembly, the alignment between the opened cross-bar of one link and the hub bore of an adjacent link is such that the protuberances on the sections of the cross-bar are both in alignment with the groove 14 provided for their reception. The operation of closing the link thus leaves the protuberance or lug 10, or rather the divided cooperating portions thereof, within the bounds of channel 11. By turning the links relatively to each other, the lug 10 is caused to lie within a region of the channel 11 to which the groove 14 does not lead. The lug 10, or the divided portions thereof, thus being enclosed between the side walls 12 of the hub, reopening of the link in the region of its cross-bar is resisted. It will be noted that the lug 10 on the cross-bar, and the groove 14 in the hub, extend in perpendicular planes. In order that assembly be made between links, the links are therefore brought into a right-angular relation to each other for insertion of the cross-bar of one into the hub of the other. Such positioning of these elements is desirable since a right-angular relation between adjacent links is one into which the links are never brought accidentally during use of the chain.

Desirably, the bore of hub 6 and the cross bar 9 are both circular in cross section. They are, however, of such relative diameter that, in assembly, one link may turn relatively to the other, longitudinally of the chain, without causing a rubbing friction between the interior surface of the hub of one link and the surface of the cross-bar lying therein. This loose engagement between links, avoiding rubbing and permitting free circulation of the pickling solution, thus avoids rapid destruction of the cross-arm because of wear accompanied by corrosion. In spite of this loose engagement, no appreciable axial turning between links is permitted. This is not only because the hub itself is of a length adequate to prevent substantial axial turning movement, but also because the engagement of lug 10 in groove

11, as a secondary function, further reduces such possibility.

Because of the structural features above considered, a chain comprising a plurality of identical links so formed runs upon a sprocket with sufficient smoothness for its intended purpose. The connection between the links is such as to give throughout the chain flexibility adequate to provide for recurrent changes in the form of the work-supporting loop of the chain in which the work lies. Also, as will readily be seen, each of the single-piece links of which the chain is composed are massive in form, and a division line permitting integration of the chain by relative engagement of the links is so positioned in assembly that corrosion at the junction line does not tend rapidly to destroy the connection between links, nor does corrosion at that point tend rapidly to impair the desired axial positioning between links.

It will be noted that the flanges 7 projected from the link hub 6 are relatively extended in the region of the hub, and that their contour lines converge to merge into the side arms 8 of the link. This structure produces in assembly work-receiving pockets between the flanges 7 of adjacent links. These pockets tend to prevent sliding movement of the stock on the chain, as the loop form of the chain is changed, and on the contrary increase the effectiveness of the chain in turning and tumbling the stock as the loop form of the chain is recurrently changed.

Because of the massive structure of the one-piece chain links, and their relative interlocking in assembly, the chain is of great strength. It may, therefore, advantageously be used for general purposes as a heavy duty sprocket chain. In such uses, other than the uses herein particularized, the sprocket chain obviously may be made of a metal, such as iron or steel, which is not acid-resistant.

Other qualities which, coupled with those immediately above noted, render my chain of great utility as a general purpose, heavy duty chain are the smooth running qualities of the chain, and the fact that the hub and cross-bar of each of the chain links are so positioned between the side arms as to give the chain a fixed pitch diameter in both directions throughout the chain. Because of this latter quality, the chain may be reversed in its mounted position, without impairing the operation of the chain, as the chain becomes worn in use. This reversibility, as made a property of a sprocket chain formed of one-piece, interlocked links, is of importance in supplementing the strength and durability attendant upon these other features of the chain.

Various modifications in the form of the links and in their relative arrangement, falling within the ambit of the appendant claims, may be made without departing from the spirit of my invention.

I claim as my invention:

1. A sprocket chain comprising a plurality of identical one-piece links, each of which said links comprises side arms, a hub lying between the side arms, a cross-bar adapted to lie within the hub of an adjacent link, said cross-bar being interrupted part-way of its length to provide for opening of the cross-bar to span and as reclosed to be forced into the hub of an adjacent link, protuberances on the cross-bar to both sides of the interruption therein, the link hub having an interior accessible channel adapted to receive the cross-bar protuberances of an adjacent link thereby

in assembly to resist reopening of the adjacent link cross-bar.

2. A sprocket chain comprising a plurality of identical one-piece links, each of which said links comprises side arms, a hub lying between the side arms, and a cross-bar adapted to lie within the hub of an adjacent link, said cross-bar being interrupted partway of its length to provide for opening of the cross-bar to span and as reclosed to be forced into the hub of an adjacent link, the said hub and the said cross-bar having thereon means effective between adjacent links arranged to provide an interlocking engagement arranged in assembly to prevent reopening of a hub-inserted cross-bar.

3. A sprocket chain comprising a plurality of identical one-piece links, each of which said links comprises side arms, a hub lying between the side arms, and a cross-bar adapted to lie within the hub of an adjacent link, said cross-bar being interrupted partway of its length to provide for opening of the cross-bar to span and as reclosed to be forced into the hub of an adjacent link, the hub bore and the cross-bar being of such relative cross-sectional area as to give therebetween a loose engagement providing in assembly free turning movement between links longitudinally of the chain without complete surface contact between the interior hub surface of one link and the cross-bar surface of an adjacent link and the hub being of a length adequate to prevent substantial relative axial turning of the links.

4. A sprocket chain comprising a plurality of identical one-piece links, each of which said links comprises side arms, a hub lying between the side arms, a cross-bar adapted to lie within the hub of an adjacent link said cross-bar being interrupted partway of its length to provide for opening of the cross-bar to span and as reclosed to be forced into the hub of an adjacent link, the said hub and the said cross-bar having thereon means effective between adjacent links arranged to provide an interlocking engagement arranged

in assembly to prevent reopening of a hub-inserted cross-bar, and extended flanges on the hub of each link merging into restricted regions of the side arms, the flanges of adjacent links in assembly providing work-receiving pockets

5

5. A sprocket chain comprising a plurality of identical one-piece links, each of which said links comprises side arms, a hub lying between the side arms, a cross-bar adapted to lie within the hub of an adjacent link, said cross-bar being interrupted partway of its length to provide for opening of the cross-bar to span and as reclosed to be forced into the hub of an adjacent link, the said hub and the said cross-bar having thereon means effective between adjacent links arranged to provide an interlocking engagement arranged in assembly to prevent reopening of a hub-inserted cross-bar, and the hub bore and the cross-bar being of such relative cross-sectional area as to give therebetween a loose engagement providing in assembly free turning movement between links longitudinally of the chain without complete surface contact between the hub surface of one link and the cross-bar surface of an adjacent link.

6. A sprocket chain comprising a plurality of identical one-piece links, each of which links comprises side arms, a hub lying between the side arms, and a cross-bar adapted to lie within the hub of an adjacent link, said cross-bar being interrupted partway of its length to span and as reclosed to be forced into the hub of an adjacent link, the said hub and the said cross-bar having thereon means effective between adjacent links to provide an interlocking engagement arranged in assembly to prevent reopening of a hub-inserted cross-bar, and the said hub and cross-bar of each link being so mounted between the side arms of the link that in the chain assembly there is a fixed pitch diameter in both directions of the chain.

JOHN L. GERBER.
